R. J. Gardner
HIS ATTORNEY

UNITED STATES PATENT OFFICE.

JOHN HAYS HAMMOND, JR., OF GLOUCESTER, MASSACHUSETTS.

AUTOMATIC ANTENNA SYSTEM.

Original application filed July 9, 1920, Serial No. 395,018. Patent No. 1,542,938, dated June 23, 1925.
 Divided and this application filed December 2, 1922. Serial No. 604,624.

Some of the objects of the present invention are to provide means for maintaining a wireless receiving apparatus in a receptive condition after an antenna to which it is responsive has been grounded by accident or shell fire; to provide means for automatically substituting an operative antenna for an antenna which has been rendered inoperative by grounding; to provide a receiving apparatus having a plurality of antennae one of which is normally operative for receiving purposes and the remaining antennae inoperative, and means for automatically substituting for and rendering operative one of the remaining antennae in case the operative antenna becomes grounded; to provide means for automatically substituting a sound wave responsive means for an antenna responsive means in case the antenna means is rendered inoperative; and to provide other improvements as will hereinafter appear.

In the accompanying drawing there is shown diagrammatically one form of wireless receiving apparatus embodying the invention.

This application is a division of application, Serial No. 395,018, filed July 9, 1920, for improvements in automatic antenna system by the same inventor.

Referring to the drawing, a receiving apparatus 10 of any well known form, responsive to impulses of radiant energy, is graphically represented and arranged to control a desired mechanism 11 such as the steering control of a torpedo, vessel or other marine body. This mechanism 11 is also arranged to be independently controlled by a receiving apparatus 12 of any well known form responsive to sound waves, the apparatus 12 being operatively connected to a receiving diaphragm 13, here shown as located in the body of a trailer 14, though it may be located at any suitable place on the torpedo or vessel itself.

For operating the receiving apparatus 10, it is included in a tuned circuit 15 having a secondary coil 16 inductively coupled to a primary coil 17 which forms part of an open aerial circuit grounded at 18 and including a battery 20 shunted by a condenser 21 and a conductor 22.

For the purpose of receiving transmitted radiant energy signals a plurality of antennae are employed, in the present illustration three are shown, 24, 25 and 26, support-

ed respectively at different locations and so arranged and connected that but one at a time is responsive to transmitted signals. In the preferred form the antenna 24 is normally responsive and is connected by a lead 60 39 through suitable insulators to one side of a tuning coil 31, the other side of which is connected by a conductor 32 to a terminal submerged in a liquid conducting material 92 such as mercury, contained in a receptacle 93 made of suitable insulating material. The receptacle 93 is closed at the bottom by a conducting plug 96 of fusible material which is electrically bonded to the conductor 22 and leads to the battery 20 and 70 shunt circuit of condenser 21 thus completing the receiving circuits. The receptacle 93 is suitably supported within a container 97 having a pocket 98 formed in the bottom portion, through the walls of which 75 two terminals 100 and 101 are led, the former having a conductor 102 connected to the conductor 22. The receptacles 94 and 95 are similarly constructed being respectively provided with fusible conducting plugs 103 and 80 104, containers 105 and 106 having pockets 107 and 108, the pocket 107 having two terminals 110 and 111 and the pocket 108 having two terminals 112 and 113. The terminal 101 is connected by a conductor 114 to 85 the fuse plug 103 and has a branch 115 connected to the terminal 110. The terminal 111 is connected by a conductor 116 to the fuse plug 104. The terminal 112 is connected to the conductor 90 previously described as 90 leading to the radiosonic receiving apparatus 12 and the terminal 113 is connected to the conductor 91 leading to the receiving sound wave device 13.

In the operation of the form of the invention shown, the antenna 24 is normally connected to the ground 18 through the tuning coil 31, the mercury in the receptacle 93, fusible plug 96, wire 22 and condenser 21 to the primary coil 17. Signals are thus receivable by the antenna 24 to operate the steering mechanism 11.

If the antenna 24 becomes grounded, the battery 20 is short circuited through the fusible plug 96 which melts and allows the mercury 92 or other liquid conductor in the receptacle 93 to run into the pocket 98 of the container 97. This breaks the circuit from the antenna 24 and closes a circuit through the terminals 100 and 101 whereby the an- 110

tenna 25 is rendered operative by connection with the ground 18 to receive signals for controlling the steering mechanism.

In case the antenna 25 becomes grounded, 5 the battery 20 will be short circuited through the fusible plug 103 which melts, allowing the mercury to run into the pocket 107 of the container 105, thus connecting the antenna 26 with the ground 18 by way of terminals 110 and 111, so that incoming signals 10 will operate the steering mechanism 11.

Should the antenna 26 become grounded, the battery 20 will be short circuited through 15 the fusible plug 104 which melts and allows the mercury to run into the pocket 108 of the container 106, thus breaking the antenna circuit and closing terminals 112 and 113 to 20 complete a circuit by way of conductors 90 and 91 to bring the radiosonic or sound wave receiving apparatus into commission.

The construction illustrated and described herein is merely what I now consider to be the preferred embodiment of my invention and it is therefore to be distinctly understood 25 that I do not limit myself thereto as many changes may be made in point of detail and other embodiments resorted to without deviating from the true spirit of the invention as defined in the appended claims.

30 What I claim is:

1. In a wireless receiving system, a receiving apparatus, an antenna connected to said receiving apparatus, a compression wave receiving apparatus, a compression wave responsive device, and means including a fusible plug for automatically connecting said compression wave responsive device to said compression wave receiving apparatus when said antenna becomes 40 grounded.

2. In a wireless receiving system, a plurality of antennæ, a receiving apparatus responsive to all of said antennæ one at a time, and means including a plurality of 45 fusible plugs for successively connecting an operative antenna to said receiving apparatus as successive connected antennæ are rendered inoperative.

3. In a wireless receiving system, a plurality of antennæ, a receiving apparatus responsive to all of said antennæ one at a time, means normally connecting one antenna to 50 said receiving apparatus to receive signals, and means including a fusible plug and ren-

dered operative by the grounding of said 55 connected antenna for connecting another of said antennæ to said receiving apparatus.

4. In a wireless receiving system, a plurality of antennæ, a receiving apparatus responsive to all of said antennæ one at a time, 60 and means including a fusible plug for successively connecting an operative antenna to said receiving apparatus, as the successively connected antenna is rendered inoperative.

5. In a wireless receiving apparatus, a 65 plurality of antennæ responsive to high frequency etheric oscillations, a receiving apparatus responsive to the energy of said oscillations and controlled by said antennæ one at a time, a source of energy inert with 70 respect to said high frequency oscillations and means including a fusible element responsive to said source of energy after connecting one antenna to said receiving apparatus in place of another antenna. 75

6. In a receiving system for radiant energy, a plurality of wave responsive devices, 80 a signal receiving apparatus controlled thereby, means including a fusible plug in series with each of said wave responsive devices from said receiving apparatus and connecting a successive wave responsive device thereto.

7. In a receiving system for radiant energy, a plurality of wave responsive devices, 85 a signal receiving apparatus controlled thereby, means including a container for fluid conducting material and including a fusible element normally retaining said material within said container in series with 90 each of said wave responsive devices for disconnecting the respective wave responsive device from said receiving apparatus.

8. In a system of distant control by radiant energy, a plurality of antennæ for the 95 reception of radiant energy, control apparatus constructed to be responsive to radiant energy received by any one of said antennæ and means including a fusible element constructed with each of said antennæ 100 and inert during the normal operation of the system responsive to excess of current flowing in a circuit of the respective antenna.

In testimony whereof I hereunto affix my 105 signature.

JOHN HAYS HAMMOND, Jr.
